UNITED STATES PATENT OFFICE.

CLAUDE E. NEGLEY, OF INDIANAPOLIS, INDIANA.

EXCAVATING-MACHINE.

1,086,304.

Specification of Letters Patent.

Patented Feb. 3, 1914.

Application filed May 10, 1913. Serial No. 766,723.

To all whom it may concern:

Be it known that I, CLAUDE E. NEGLEY, a citizen of the United States, residing at Indianapolis, Marion county, and State of Indiana, have invented and discovered certain new and useful Improvements in Excavating-Machines, of which the following is a specification.

My invention relates to excavating machines and particularly to improvements in that type of excavating machine shown in my Patent No. 1,053,428.

The object of my present invention is to provide means to enable the excavator bucket to be dumped upon the rearward travel of the bucket along the supporting cable as well as upon the forward travel thereof under the pulling action of the load line.

With this end in view my invention is embodied in preferable form in the device hereinafter described and illustrated in the accompanying drawings.

In these drawings, Figure 1 is a side view in elevation of an excavator bucket and carrier showing the same mounted upon a slack cable; Fig. 2, is a front view in elevation and Fig. 3 is a rear view in elevation.

Referring to the drawings, 1 indicates a track cable of what is known as the "slack" type by means of which the bucket and its carrier may be raised and lowered to and from a bed of material to be excavated and along which the carrier is adapted to be drawn to move a loaded bucket from an excavating point to the point of discharge. A load line 2 is provided with an upper branch 3 and a lower branch 4, both of which are connected separately to an excavating bucket 5 and by means of which load line the bucket is drawn up into engagement with its latching means on the carrier and the carrier and bucket are drawn along the bed of material to be excavated and therefrom to the point of discharge. The lower branch 4 of the load line is connected directly to the lower front part of the bucket while the upper branch 3 runs over a pulley 6 which is mounted upon a front arm 7 of a bucket carrier 8. The end of the branch 3 is connected to a cross arm 9 extending transversely of the bucket and secured to the side walls thereof at their upper edges.

On the pivot pin 10 on which the pulley 6 is mounted, is pivoted a rigid latch member 11, the lower hook portion 12 of which

is of sufficient weight to carry the hook to normally swing rearwardly, so that it will engage the under side of a cross bail 13 fastened to the upper edges of the bucket 60 near the front end of the latter. This latch hook serves as the means for holding the bucket in load position and keeping it parallel with the carrier. The upper end of the latch member has a forked arm 15 adapted 65 to embrace the load cable and this arm is adapted to strike against a trip member 16 fixed on the main cable 1 adjacent to the point of discharge. Such point of discharge is usually located between the point of excavation and the location of the power means, such as the hoisting engine, and the bucket is drawn along the slack cable up to this point of discharge by means of power applied to the load line, and when the upper arm of the latch hook contacts with the trip on the supporting cable, the hook is thereby automatically released from the bucket and at the same time the load line is also slackened by the operator, whereupon 80 the bucket will be dumped.

The bucket carrier consists of a rigid, open, vertical frame and on the rear vertical arms of this frame the bucket is pivoted by means of a connecting bail 17.

Extending rearwardly and slightly upwardly from the upper horizontal arms of the carrier frame, are parallel extension members 18. Each of these members is provided with a series of holes 19 through 90 any of the corresponding pairs of which holes is adapted to be inserted a supporting bolt 20 on which is pivoted the side arms of a forked member or bail 21, which is open at its upper end and closed at the lower end. 95 This open bail surrounds the supporting cable and the vertical arms thereof are adapted to strike against a trip block 22 which is fixed on the said cable at a point on the far side of the excavating bed.

A transverse bolt 23 connects the two arms of the bail member at their upper ends and pivotally connecting this bolt and a similar bolt 24 mounted in the upper ends of the two members of the forked arm 15 of 105 the latch member 11, is a rod 25. By the above arrangement it will be seen that when the carrier is permitted to travel along the supporting cable to a point where the bail 21 will contact with the trip block 22, that 110 such bail will be rocked on the bolt 20, thus drawing rearwardly the rod 25 and rock-

ing the hook latch 11 on its pivot 10 so as to thereby withdraw the hook from engagement with the bucket and permit the latter to be dumped.

5. It will be seen that the above construction enables the contents of the bucket to be dumped from the front end of the latter on either side of the bed of material being excavated, which arrangement permits the 10 operator to select either the far or near side as the point of discharge for the material to be recovered and also provides the advantage of enabling the operator to excavate, preliminarily to the main operation, a few 15 loads of waste material from the top of the bed, such as sediment, dirt, etc., until the clean gravel is reached, the sediment or waste material being discharged on the far side of the bed and the material to be recovered being pulled toward the hoisting engine and discharged on the near side.

Having thus described my invention what I claim is:—

1. In an excavating apparatus in combination with a track cable, a bucket carrier mounted on said track cable, a bucket pivoted on said carrier, a load cable, means to hold said bucket in load carrying position and means operable to trip said holding 25 means upon the travel of the bucket carrier in either direction on the track cable, substantially as described.

2. In an excavating apparatus, in combination with a track cable, a bucket carrier mounted on said track cable, a bucket pivoted on said carrier and operable to dump at its front end, latching means for the bucket and means to trip said latching means upon the backward travel of the 30 bucket on the track cable, substantially as described.

3. In an excavating apparatus in combination with a track cable, a bucket carrier mounted on said cable, a bucket pivoted on said carrier and operable to discharge from its front end, a load cable, latching means to hold the bucket in load carrying position, trip means for said latching means located on the track cable intermediate the 35 point of excavation and the point of appli- 40

cation of power to the load line and trip means located on the track cable on the other side of said point of excavation, substantially as described.

4. In an excavating apparatus, in combination with a track cable, a bucket carrier mounted on said cable, a bucket pivoted on said carrier and operable to discharge at its front end, latch means mounted on the carrier near the front end thereof and engaging said bucket, connected latch tripping means at opposite ends of the carrier and trip blocks on said track cable operable to engage and trip the respective tripping means, substantially as described. 55

5. In an excavating apparatus, in combination with a track cable, a bucket carrier mounted thereon, a bucket pivoted on said carrier to dump at its front end, a rigid latch hook pivoted on said carrier and operable to engage said bucket, a trip arm extending therefrom, a trip arm mounted on said carrier at the rear end thereof, means connecting said trip arms and trip blocks corresponding respectively to said arms and 70 mounted on said track cable, substantially as described. 75

6. In an excavating apparatus, in combination with a track cable, a bucket carrier mounted thereon, a bucket pivoted on said carrier and operable to discharge at its front end, a rigid pivoted latch hook member mounted on the carrier and adapted to engage the front part of the bucket, a trip arm on said latch hook, a trip block on said track cable operable to trip said arm, said carrier having extensions projecting rearwardly, a trip arm pivoted thereto, a rod connecting said rear trip arm with said latch hook and a second trip block mounted on the track cable and operable to trip said 80 second arm, substantially as described. 85

In witness whereof, I have hereunto set my hand and seal at Indianapolis, Indiana, this third day of May, A. D. nineteen hundred and thirteen.

CLAUDE E. NEGLEY. [L.S.]
